CLOSURE CAP

Howard F. Reichenbach, Waterbury, Conn., assignor to Chase Brass & Copper Co. Incorporated, Waterbury, Conn., a corporation

Application February 23, 1940, Serial No. 320,243

4 Claims. (Cl. 215—43)

The present invention relates to improvements in closure caps for threaded application to bottles, cans, and other containers.

One of the objects of the present invention is to provide a closure cap characterized by a superior degree of neatness and attractiveness of appearance.

Another object of the present invention is to provide a superior closure cap combining low cost for manufacture with adequate strength and attractiveness of appearance.

With the above and other objects in view, as will appear to those skilled in the art from the present disclosure, this invention includes all features in the said disclosure which are novel over the prior art and which are not claimed in any separate application.

In the accompanying drawing, in which certain modes of carrying out the present invention are shown for illustrative purposes:

Fig. 1 is a view in side elevation of a closure cap embodying the present invention;

Fig. 2 is an underside view thereof;

Fig. 3 is a vertical central sectional view taken on the line 3—3 of Fig. 1, but on a larger scale;

Fig. 4 is a transverse sectional view taken on the line 4—4 of Fig. 3;

Fig. 5 is a view partly in side elevation and partly in vertical central section of the outer shell on the same scale as Figs. 3 and 4;

Fig. 6 is an underside view thereof on the scale of Figs. 1 and 2;

Fig. 7 is a view partly in side elevation and partly in vertical central section of the inner shell on the scale of Figs. 3, 4 and 5; and

Fig. 8 is a top or plan view thereof on the scale of Figs. 1, 2 and 6.

The particular closure cap herein chosen for the purposes of illustrating the present invention, comprises an outer shell generally designated by the reference character 10 and an inner shell generally designated by the reference character 11.

The outer shell 10 above referred to, has, in the particular closure cap shown, a substantially-spherical, hollow body-portion 12 from the lower edge of which inwardly extends an integral substantially-horizontal flange 13. Formed integral with the inner portion of the flange 13 just referred to, is a substantially cylindrically-contoured neck 14 extending downwardly from the said flange 13 in parallelism with the vertical central axis of the outer shell 10. As will be noted by reference to the drawing, the neck 14 is smaller in diameter than the diameter of the

body-portion 12 for purposes as will hereinafter appear.

The inner shell 11 above referred to is of inverted cup-shaped form and includes a substantially cylindrically-contoured neck 15 sized and shaped exteriorly to be snugly received with a force-fit into the interior of the neck 14 of the outer shell 10. Formed integrally with the lower end of the neck 15 of the inner shell 11, is a reversely-bent finishing-skirt 16 sloping upwardly and outwardly and preferably snugly engaging the outer shell 10 at a point adjacent the juncture of the body-portion 12 and the flange 13 thereof, as is especially well shown in Fig. 3.

15 The finishing-skirt 16, just referred to, is preferably spherically contoured to complement the substantially-spherical contour of the body-portion 12 of the outer shell 10.

The inner shell 11 also includes a horizontally-extending flange 17 integrally united at its outer portion with the upper end of the neck 15 and integrally joined at its inner portion with the lower end of the hollow body-portion 18 of the inner shell 11. The periphery of the said body-portion 18 is rolled or otherwise suitably formed to provide threads 19 for engagement with the threaded terminal of a bottle or other container.

At the upper end of its body-portion 18 the inner shell 11 is formed with an integral substantially-flat end- or top-wall 20 providing a seat for a sealing gasket 21 which latter is designed and adapted to be seated against the upper surface of the neck of a bottle or other container to provide a fluid-tight seal.

35 By constructing and arranging the respective outer shell 10 and inner shell 11 as shown, a neat, attractive and rugged closure cap is provided which may be manufactured economically.

The invention may be carried out in other 40 specific ways than those herein set forth without departing from the spirit and essential characteristic of the invention, and the present embodiments are, therefore, to be considered in all respects as illustrative and not restrictive, and 45 all changes coming within the meaning and equivalency range of the appended claims are intended to be embraced therein.

I claim:

1. A closure cap comprising: an outer shell 50 having a substantially-spherically-contoured body-portion and also having at its lower end a neck-portion having a diameter smaller than the diameter of the said body-portion and constructed and arranged to receive a cylindrically-contoured portion of an inner shell; and an inner

shell of inverted substantially cup-shaped form and including a threaded portion extending upwardly into the interior of the spherically-contoured body-portion of the said outer shell, a neck-portion of substantially-cylindrical form snugly fitting within the cylindrically-contoured neck-portion of the said outer shell, the said inner shell also having a finishing-skirt of substantially-spherical exterior contour and formed integral with and reversely extending from the lower end of the neck-portion of the said inner shell and encircling and substantially concealing the reduced-diametered cylindrical neck of the said outer shell, the said finishing-skirt complementing and forming a continuation of the substantially-spherical outer contour of the body-portion of the said outer shell.

2. A closure cap comprising: an outer shell having a substantially-spherically-contoured body-portion and also having at its lower end a neck-portion having a diameter smaller than the diameter of the said body-portion and constructed and arranged to receive a cylindrically-contoured portion of an inner shell; and an inner shell of inverted substantially cup-shaped form and including a threaded portion extending upwardly into the interior of the spherically-contoured body-portion of the said outer shell, a neck-portion of substantially-cylindrical form having a larger diameter than the said threaded portion and snugly fitting within the cylindrically-contoured neck-portion of the said outer shell, the said inner shell also having a finishing-skirt of substantially-spherical exterior contour and formed integral with and reversely extending from the lower end of the relatively large-diametered neck-portion of the said inner shell and encircling and substantially concealing the reduced diametered cylindrical neck of the said outer shell, the said finishing-skirt complement-

ing and forming a continuation of the substantially-spherical outer contour of the body-portion of the said outer shell.

3. A closure cap having an ornamental outer surface and comprising: an outer shell providing the major portion of said ornamental outer surface and including at its lower end an inwardly-extending flange, and a substantially-cylindrical neck-portion depending from the inner portion of said flange; and an inner shell of inverted substantially cup-shaped form including a threaded portion extending upwardly into the interior of said outer shell, a substantially-cylindrical neck-portion fitting and secured in the interior of the cylindrical neck-portion of said outer shell, and a finishing-skirt integral with the lower end of the neck-portion of said inner shell and surrounding, and flaring upwardly and outwardly away from, the cylindrical neck-portion of said outer shell to form the lower part of said ornamental outer surface.

4. A closure cap having an ornamental outer surface and comprising: an outer shell providing the major portion of said ornamental outer surface and including at its lower end an inwardly-extending flange, and a substantially-cylindrical neck-portion depending from the inner portion of said flange; and an inner shell of inverted substantially cup-shaped form including a threaded portion extending upwardly into the interior of said outer shell, a substantially-cylindrical neck-portion fitting and secured in the interior of the cylindrical neck-portion of said outer shell by a force fit, and a finishing-skirt integral with the lower end of the neck-portion of said inner shell and surrounding, and flaring upwardly and outwardly away from, the cylindrical neck-portion of said outer shell to form the lower part of said ornamental outer surface.

HOWARD F. REICHENBACH.
